BURGLARPROOF POCKET

Filed March 19, 1929

By his Attorney *Emil Reichmutter*
Marie Relling

UNITED STATES PATENT OFFICE

EMIL TEICHMUELLER, OF NEW YORK, N. Y.

BURGLARPROOF POCKET

Application filed March 19, 1929. Serial No. 348,152.

- This invention relates to improvements in wearing apparel, particularly in the pockets of such apparel, and more particularly to a burglarproof pocket, and it is the principal object of my invention to provide a pocket which is adapted to be securely closed in a simple manner and which will foil or frustrate any attempt to stealthily open the pocket and to withdraw its contents.
- 10 Another object of my invention is the provision of a burglarproof pocket the constituent elements of which can readily be applied to any garment, coat, vest, trousers, etc., without material change in the garment.
- 15 A further object of my invention is the provision of a burglarproof pocket of the above type of simple and therefore inexpensive construction, yet durable and efficient in operation.
- 20 A still further object of my invention is the provision of a burglarproof pocket equipped with a closing tongue slidably secured to the material of the garment and adapted to engage a slot in a reinforcing member formed on the upper edge of the pocket material, the tongue adapted to be turned about a hinge.

These and other objects and advantages of my pocket will become more fully known as the description thereof proceeds, and will then be specifically defined in the appended claims.

In the accompanying drawing, forming a material part of this disclosure:

- 35 Fig. 1 is a fragmentary front elevation of a coat equipped with a burglarproof inner pocket constructed according to my invention, closed.
- 40 Fig. 2 is a section on line 2—2 of Figure 1, with the pocket closed.
- Fig. 3 is a similar section with the pocket half open.
- Fig. 4 is a perspective view of a closure member.
- 45 Fig. 5 is a perspective view of a pocket reinforcing member.
- Fig. 6 is a view similar to Figure 1 with the pocket half open.
- 50 Fig. 7 is a section on line 7—7 of Figure 6,

the upper or male part of the lock pulled out to allow access to the pocket.

As illustrated, a coat 10 has formed therewith an inner pocket 11 in the usual well known manner, the upper edge of which is reinforced by an element 12 preferably made of light metal such as for instance aluminum, japanned tin etc., having an inner member 13 adapted to be secured to the inner face of the pocket near the upper edge of pocket 11 by suitable fastening means passing through holes 14. Integrally made with member 13 is a member 15 at the lower end thereof adapted to be secured to the inner face of the pocket 11 by the same fastening means securing member 13 to the material of the pocket, so that a pocket or slot 16 is formed between both members 13 and 15 closed at the bottom as at 17.

Integral with the upper edge of member 15 is lip 18 angularly bent to member 15 and adapted to grip over the upper edge of material 11 forming the pocket and secured thereto in any well known suitable manner by fastening means as for instance eyelet 19 passed through openings 20 in lip 18.

To the inner face of the material of coat 10 near the upper end of the pocket 11 a strengthening piece of fabric 21 is stitched to which is secured one member 22 of a guide element for the pocket closure, by means of a suitable fastening means passing through openings 24 of a reinforcing strip 25 and through openings 23 in the upper edge of said member 22.

Integrally made with member 22 and bent, at an angle thereto, but adapted to engage the inner face of member 22 are arms 26 which form with the arms 27 of the reinforcing strip 25 guides for loops 28 formed at the lower ends of plate 29 to the upper end of which a tongue 30 is hingedly secured, as at 31, which is adapted to enter slot 16 between members 13 and 18 if the pocket is to be closed.

The operation of my device is very simple and will be fully understood by the reading of the specification and simultaneous inspection of the drawing.

It will be understood that I may make such

changes in the construction of my pocket as come within the scope of the appended claims without departure from the spirit of my invention.

Having thus described my invention, what I claim as new, and desire to secure by Letters Patent is:

1. Burglarproof pocket comprising a slotted reinforcing member for the upper 10 edge of the material forming the pocket, a member adapted to be attached to a suit near the upper edge of the pocket, a pair of arms formed with said member, a reinforcing member therefor, arms on said reinforcing 15 member adapted to form a guide with said first named arms, a pair of sockets adapted to slide along said guide, a plate on which said sockets are formed, and a tongue hinged- 20 ly secured to the upper edge of said plate and adapted to enter in its lower position into the slot of said first named reinforcing member to close the pocket and to allow a use of the pocket in its elevated position.
2. In a burglarproof pocket, a keeper 25 member and a member adapted to be secured to the material of a suit at the upper edge of said pocket, said member comprising a blank adapted to be secured to the material of the suit, a reinforcing member for said 30 blank, arms formed with said blank and arms formed with said reinforcing member to form guides in their folded positions, one pair of arms against the other pair, a sliding plate, sockets formed at the lower end there- 35 of, adapted to slide along the guide formed by said pairs of arms, and a tongue hinged to the upper edge of said plate adapted to engage in its lower position said keeper mem- 40 ber and in its elevated position allowing a use of said pocket.

In witness whereof I have signed my name to this specification.

EMIL TEICHMUELLER.
